CLAIM

The ornamental design for a pull out spice rack, as shown and described.

DESCRIPTION

FIG. 1 is a top perspective view of a pull out spice rack, showing my new design;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the figures are for the purposes of illustrating portions of the pull out spice rack, which form no part of the claimed design.

1 Claim, 8 Drawing Sheets
